UNITED STATES PATENT OFFICE.

ALBERT D. SMITH, OF DETROIT, MICHIGAN.

REVOLVING-HOOK SEWING MACHINE.

1,415,268.

Specification of Letters Patent. Patented May 9, 1922.

Application filed July 30, 1918. Serial No. 247,423.

To all whom it may concern:

Be it known that I, ALBERT D. SMITH, a citizen of the United States, residing at Detroit, in the county of Wayne and State of Michigan, have invented certain new and useful Improvements in Revolving-Hook Sewing Machines, of which the following is a specification.

This invention pertaining in general to revolving hook sewing machines, is an improvement on that type of machine described in my Patent No. 1,261,170, known as a two-spool machine. Such a machine is exemplified by the provision of a lower 10 thread receptacle adapted to carry an ordinary spool of thread as distinguished from shuttle machines and those which carry a bobbin of relatively small capacity upon which the lower thread must be wound from 15 a spool. The sewing machine described in 20 said patent is further characterized by its novel lower thread receptacle which is designed to carry both domestic and foreign spools of a wide range of sizes, and even to 25 carry a ball of thread or yarn instead of a spool in cases where certain fancy work or special forms of sewing are required.

A lower thread carrier or receptacle of this kind, in combination with a revolving 30 hook, necessarily requires that a large loop of upper thread be passed around the receptacle by the hook or looper. And because of the conditions peculiar to revolving hook machines of this type, and especially when 35 a rotary take-up is employed, the thread loop after being cast off the hook is exceedingly difficult to control without breaking or putting undue tension on the thread. This thread loop or loop end before being 40 drawn up by the take-up has a tendency to twist, whirl and catch on any near part of the machine, all of which is augmented by the increased momentum of the thread when operating at high speed. In addition 45 to the liability of breaking the thread under these unfavorable conditions, an unusual tension is imposed by twisting of the loop end, which results in imperfect stitches.

The primary object of the present invention is to provide an improved means for controlling the thread passing around the lower thread receptacle, which shall positively guide the loop at every stage without causing undue tension on the thread, there- 50 by precluding the occurrence of any undue

slack or looseness in the loop which might impair the operation in any respect. The manner of attaining complete control of this large loop as it is passed around the lower thread receptacle is fully set forth in the 60 following specification.

Further objects of my invention are to improve the construction of the lower thread receptacle, thread tension and stationary support for the thread receptacle, and to 65 provide a rotary-hook structure having a detachable hook point, especially desirable as will appear hereinafter.

With the foregoing objects in mind, I have also aimed to so design the several parts 70 that they are capable of production at a comparatively low cost and will practically and effectually serve the purposes desired of a commercially successful sewing machine.

Other objects and attendant advantages 75 will be appreciated as the invention becomes better understood by reference to the following description when considered in connection with the accompanying drawings, in 80 which—

Figure 1 is an end view of a sewing machine embodying my improvements;

Figs. 2 and 3, sectional views taken substantially on the lines 2—2 and 3—3, respectively, of Fig. 1;

Fig. 4, a rear view of the thread receptacle removed from the machine;

Figs. 5 and 6, views of the thread receptacle from opposite ends thereof;

Fig. 7, a detail plan view of the rotary hook with the retaining ring attached;

Fig. 8, a face view of the rotary hook with the retaining ring removed;

Figs. 9 and 10, plan and face views, respectively, of the retaining ring;

Figs. 11, 12 and 13, plan, face and side views, respectively, of the support for the thread receptacle; and

Fig. 14, a development of the thread-receptacle support.

Since one of the chief features of this invention resides in the control of the relatively large loop that is passed around the lower thread receptacle, I have illustrated 105 my improvements in full size, so that the dimensions of the loop and the conditions present might be better appreciated. Any suitable take-up may be employed, although I prefer one of the rotary type, as it is more 110

efficient, runs more smoothly and quietly, and requires less power to operate. Those parts, the particular construction of which is not important, consists of a work-plate 15, head 16, needle-bar 17, presser-bar 18 and a rotary take-up 19 having a single eccentric thread pin 21. In this form of take-up, the upper thread 22 enters between the take-up disks at the lower portion thereof, 10 being guided over a stud 23, passes over the thread pin 21 and leaves the take-up disks directly over the needle-way, being guided by a stationary finger 24, and then passes through the eye of the needle. This particular rotary take-up forms the subject matter of my copending application, Serial No. 250,651, filed Aug. 20, 1918.

The feed mechanism is omitted as its particular construction is not essential to my 20 present improvements.

As mentioned above, the lower thread is supplied from an ordinary spool, and the thread receptacle is constructed to carry spools of various shapes and sizes, and thus 25 the same thread receptacle will serve to carry either the ordinary domestic spool or the differently shaped foreign spool, and will also carry a ball of thread, or even yarn. Thus the present machine may be used for 30 various forms of fancy sewing impossible to accomplish with ordinary machines, due mainly to the limitations imposed by the construction of their thread receptacles or holders and to their inability to properly 35 control the thread. My improved thread receptacle, designated generally by reference character 25 and shown in detail in Figs. 4 to 6 inclusive, is preferably in the form of an open-top case having downwardly converging front and back walls 26 and 27 and between and upon which a spool is adapted to revolve. These front and rear walls are joined by end walls 28 and 29, and through the lower end of these end walls 40 is passed a pivot member 31, which is supported at its ends on lugs 32 on the stationary support designated generally by character 33. This support is mounted on an annular race-way on the revolving-hook 45 structure which will be described later. The support 33 is shaped to provide an interior opening 34 in which the thread receptacle is disposed, and it will be noted that the thread receptacle is preferably supported 50 at a slight inclination so that its opened top is tilted toward the front of the machine to facilitate placing a spool into and removing it from the receptacle through the opening 55 in the work-plate, which opening is normally covered by a hinged door 36. The thread receptacle may be swung outwardly 60 on its pivot 31 to a thread-receiving position and inwardly to the operative position shown in Figs. 1 and 3. This latter position 65 is limited by contact of the laterally pro-

jecting abutment 37 on the wall 29 against the support 33, and movement forwardly is prevented by the adjacent spring stop 38, which engages the opposite end of the supporting member 33. In opening and closing 70 the thread receptacle, this resilient element 38 will be sprung out of the way as will be manifest. The opposite end 28 of the receptacle is also provided with an upstanding resilient portion 39 adapted to bear against 75 the adjacent wall of the member 33 to frictionally hold the thread receptacle in position, yet allowing it to be easily swung to its different positions. A cutaway 41 is formed in the front corner of the receptacle 80 at the side thereof first approached by the loop when it is drawn down by the hook extending into the front wall, as shown, and provides an upright surface 42 which continues upwardly forming a curved thread-guiding surface 43 extending substantially 85 above the body proper of the thread receptacle and terminating in a rounded top. The curved surface 43 is formed along one edge of the upstanding finger 44 integral with 90 the front wall 26 of the thread receptacle, and the purpose of the cutaway 41, the surface 43 and the finger 44 will be mentioned later.

Means is now provided for applying a 95 tension to the lower thread as it leaves the receptacle 25. The thread spool is preferably positioned in the receptacle so that the thread is drawn from the underside of the spool toward the front wall 26 and passes 100 through an eye 45 substantially in the vertical plane of the needle-way. When threading the machine, the receptacle is swung to its open position, a spool of thread placed in the receptacle, and the loose thread end 105 passed downwardly through the curved slot 46 to the eye 45 and entered beneath the resilient end 47 of a spring tension. This tension is in the form of a spring, the resilient end 47 of which is constantly urged 110 against the front wall of the thread receptacle to impose a tension on the thread passing between said end and wall. The opposite end of the spring is covered by a cap 48 having beveled edges so as not to obstruct the loop, and a single screw 49 passing through the cap 48 and the spring secures both of these parts to the receptacle. An intermediate adjusting screw 51 passing through 115 the cap and the spring threadingly engages the front wall 26 and is adapted to be adjusted to vary the tension of the spring as 120 will be manifest.

The member 33 which carries the thread receptacle is, in effect, a stationary shuttle. 125 This member is preferably pressed from sheet metal to substantially the shape shown in Fig. 14. This blank provides a cutaway 52, a loop spreader 53 and a projection 54 from which extends fingers or arms 55, 56 130

and 57. As shown in Figs. 11 to 13 inclusive, the portion 54 is bent at right angles to the main body of the member 33, the finger 55 is turned upwardly to form a retaining finger 5 co-operating with a fixed part of the machine for holding the member 33 against rotation in the race-way, and the fingers 56 and 57 are respectively turned toward the main body portion in the manner shown to 10 provide a continuous thread-guiding surface, the purpose of which will be described later. Attention is called, however, particularly to Fig. 11 which shows that the thread-guiding surface 58 extends continuously 15 from side to side of the needle-way from a high point in front of the retaining finger 55 and inclines laterally toward both sides of the member 33, the finger 57 being turned downwardly a substantial distance along one 20 side of the member.

When the stationary support 33 is positioned in the race-way of the rotary hook, it assumes the position shown in Fig. 1, the upstanding finger 55 projecting into the 25 opening 59 in a bar 61 fixed to the frame of the machine. The final loop end as it is drawn up passes between the finger 55 and a wall of the opening 59, and I prefer to face said finger with a resilient spring finger 30 62 so that this loop end is drawn between the resilient finger and stationary part so as to avoid a sharp pull on the thread at this point. The bar 61 is shaped to provide a depending thread-guiding portion 63, the 35 lower surface of which extends below and in close proximity to the rounded peak of the thread-guiding finger 44 on the thread receptacle, as indicated in Figs. 1 and 2. The undersurface 64 of the depending portion 40 63 co-operates with the thread-guiding surfaces on the finger 44 in a manner described later.

Another stationary thread controller or 45 guide is provided in the form of a part 65 fixed to a stationary part of the machine in front and at one side of the thread receptacle and extending inwardly to a point in front of and in proximity to the upright portion of the finger 57 and thence upwardly and 50 terminating in an arm 66 having a thread-guiding surface 67 disposed within the thread-guiding surface 58 and inclined upwardly substantially parallel with the plane of the member 33 and terminating substantially 55 in the vertical plane of the needle-way, viewing Fig. 1. The function of this thread controller will also appear later.

Coming now to the rotary hook structure, and referring particularly to Figs. 3 and 7 60 to 10 inclusive, it will be seen that the annular body or ring 68 is of the usual construction and is fixed to a shaft 69 suitably journaled on the frame of the machine. In this case, the shaft 69 is driven three revolutions 65 to one revolution of the take-up. The hook

ring 68 is provided with an annular race-way 71, in which the receptacle-supporting member 33 is mounted, and a retaining ring 72 suitably secured to the ring 68 holds the member 33 in position. I have provided on 70 the inner surface of the retaining ring a series of tangentially disposed indentures 73 having sharpened edges for the purpose of instantly cutting the thread if by chance it should become engaged in the race-way. 75

Attention is called to the construction of the hook point 74. So far as I am aware, the hook point has always been made integral with the revolving hook body or ring, and I have observed that in many instances 80 where revolving-hook sewing machines operate ineffectively and break the thread, the real cause is due to the fact that the hook has either been worn blunt at the point or broken off. Thus, it is commonly found that 85 after a revolving-hook sewing machine has been used for a long period, it will skip stitches, break the thread and especially fray all silk thread. If it is known that the fault lies in the hook point the entire revolving 90 body must be replaced by a new one, which requires the attention of an expert to make such a change. This difficulty and expense I have obviated by the provision of a revolving hook structure having a detachable hook 95 point, which if worn or damaged can be quickly replaced by any inexperienced operator at a comparatively small cost. Referring to Figs. 7 and 8, it will be seen that the periphery of the revolving-hook ring 68 100 100 is cut away at 75 to receive the detachable hook point, which is preferably in the form of a steel stamping shaped to provide a shank 76 fitting in said cutaway 75 and rigidly secured to the hook ring by means of screws 77, and further shaped to provide the hook point 74 above mentioned, to properly engage the loop formed by the needle. The retaining ring 72 overlaps the shank of the detachable hook as clearly shown in Fig. 7, so as 110 to cover the joint between the shank and the hook ring. It will be readily apparent that a hook point of this character may be quickly and easily detached by any inexperienced operator, and that the cost of replacing a worn or blunted hook point 115 amounts to simply the cost of the hook itself instead of the entire hook ring and the time of an experienced operator, as formerly.

Means is provided for preventing retroaction of the revolving hook for the purpose described and claimed in my patent mentioned above, consisting of a ball friction stop 78, shown in Fig. 1, for engaging the periphery of the hook ring 68. 120

Coming now to the operation of my improvements, the needle is threaded in the usual way, and a spool of thread is placed in the receptacle 25 in the manner described above, with the thread emanating from the 130

eye 45 and passing upwardly beneath the tension 47 and allowed to simply hang forwardly over this tension spring sufficient length to be gathered up by the loop of up- 5 per thread when the same is drawn up. The needle descends to its lowest point and then ascends the proper distance to form a small loop of upper thread, which the hook point 74 enters, revolving in a counter-clockwise 10 direction, viewing Fig. 1. The hook carries the loop into contact with the spreader point 53, which divides the loop, throwing the outer half forwardly over the stationary receptacle support 33 and the inner half rear- 15 wardly over said support. As the hook advances downwardly, carrying the loop, the take-up lets down just sufficient thread to pass around the receptacle and its support. It will be manifest that in view of the com- 20 paratively large size of the thread receptacle, an unusually large loop must be formed and this loop must be so controlled that after being cast off the hook point it will be impossible for the loop to foul the 25 hook or to twist, snarl or catch on any part of the machine. In order to completely control the loop at each stage and without imposing an unusual tension on the loop, which would be detrimental to the action, I 30 have shaped the thread receptacle in the peculiar manner described above and have provided various stationary thread controllers, each having a definite function, as will be presently seen. As the hook point descends, 35 the outer and inner portions of the loop will engage and be spread outwardly by the diverging outer and inner walls of the thread receptacle. When the hook reaches approximately the point X, the full amount of slack 40 has been drawn down, and at this point the greatest dimension must be embraced by the loop. At this point, the outer portion of the loop drops into the cutaway 41 formed in the end of the thread receptacle first ap- 45 proached by the loop, and relieves the strain on the thread while it is being drawn over the back wall and the forward end of the thread receptacle. As the hook point ascends, the forward or outer portion of the 50 loop comes into contact with the lower end of the stationary arm 65, which draws the thread inwardly and downwardly and slightly advances the thread along the surface 42 and also advances the end of the loop 55 to the left and out of the path of the hook point. Thus, just after the loop is cast off the hook, its forward portion is held in position by the surface 42 on the thread receptacle and between the inner edge 67 of the 60 stationary arm 66 and the outer surface 58 of the arm 57. The loop end will now be drawn up by the take-up and will be held by the several guide surfaces in a spread-out condition so as to preclude the tendency of 65 any slack formation which might swirl or

twist. Thus the loop end is drawn up over the forwardly positioned surfaces 43 and 58 and the inner surface 67, it being especially noted that the surface 58 is continuous and bars any approach of either the loop or 70 lower thread to the needle-way or the path of the hook point, which while the loop is still guided on the three surfaces mentioned, moves through its upper cycle and passes the needle-way. As the loop is drawn up still 75 further, it will first leave the surface 67 and then be drawn over the rounded top of the finger 44, it being manifest that during these later stages the loop will be guided in constant contact with the surface 43 and against 80 flying upwardly by reason of the guide surface 64 of the stationary arm 63. When the loop end finally draws over the end of the finger 44 it is so small and the take-up pin is rising so rapidly that the very short loop 85 end will be quickly drawn up past the spring finger 62 and the stitch completed.

From the foregoing, it will be seen that a loop is passed around a comparatively large thread receptacle and positively controlled at each stage in a manner, which by practical demonstration shows that no unusual tension is imposed on the loop and that even the finest of silk threads are controlled just as effectively as the heavier threads. 90 While the description of the action must necessarily for the purpose of clarity consider the position of the thread loop at different stages as it were, it should be understood that the action is a continuous one and 95 that the loop is passed around the receptacle with such rapidity and at such high speed that its course, when the machine is in operation, is not distinguishable. With the result of this control of the thread, better 100 stitches are formed, because the loop is drawn up straight and the full tension of the take-up may be applied in drawing the stitch tight rather than for untwisting a 105 badly snarled loop as commonly occurs in 110 many types of rotary-hook sewing machines now on the market. Attention is also called to the fact that regardless of the length of the loose end of the lower thread hanging from the thread receptacle, there is no 115 chance of this loose end being caught by the revolving hook and being drawn into the race-way, a common occurrence in other types of revolving-hook machines if a loose lower thread end is left. In the present case, 120 this thread end will be held out of the hook path by the thread-guiding surface 58.

It is believed that the foregoing conveys a clear understanding of the principles and operation of my improvements and of the 125 objects prefaced above, and it should be understood that while I have illustrated and described but one working embodiment of my invention, various changes might be made in the proportions, construction and 130

arrangement without departing from the spirit and scope of the invention as expressed in the appended claims.

I claim:

5. 1. In a revolving hook sewing machine, the combination with a revolving hook, of a thread receptacle within the revolving hook, having an outer wall adapted to swing from an outer open position to an inner operative position, said outer wall having a thread-guiding surface extending above the thread body proper within the receptacle for guiding the loop end after it has been cast off the hook. 10
15. 2. In a revolving hook sewing machine, the combination with a revolving hook, of a thread receptacle within the revolving hook, having an outer wall adapted to swing from an outer open position to an inner operative position, said outer wall having a thread-guiding surface extending above the thread body proper within the receptacle, and a depending stationary thread guide in co-operative relation with said upstanding guiding 20 surface for guiding the loop and holding the thread against said upstanding surface after the loop has been cast off the hook. 25
3. In a revolving hook sewing machine, the combination with a revolving hook, of a 30 thread receptacle within the revolving hook, having an outer wall adapted to swing from an outer open position to an inner operative position, and a thread-guiding surface on said outer wall for guiding the loop after 35 it has been cast off the hook and is being drawn up.
4. In a revolving hook sewing machine, the combination with a revolving hook, of a 40 thread receptacle within the revolving hook, having an outer wall adapted to swing from an outer open position to an inner operative position, and a thread-guiding surface on said outer wall for guiding the loop after 45 it has been cast off the hook and is being drawn up, said surface being disposed at the side of the thread receptacle first approached by the loop and extending upwardly above the thread receptacle. 5. In a revolving hook sewing machine, 50 the combination with a revolving hook, of a thread receptacle within the revolving hook, having an outer wall adapted to swing from an outer open position to an inner operative position, and a thread-guiding surface on 55 said outer wall for guiding the loop after it has been cast off the hook and is being drawn up, said surface being disposed at the side of the thread receptacle first approached by the loop and extending from a 60 lower point within the upper and lower ends of the thread receptacle, upwardly and above the thread receptacle proper. 6. In a revolving hook sewing machine, 65 the combination with a revolving hook, of a thread receptacle within the revolving hook,
- having an outer wall adapted to swing from an outer open position to an inner operative position, said outer wall having a cutaway in its end first approached by the loop whereby to provide certain clearance for the loop as it is drawn around the thread receptacle. 7. In a revolving hook sewing machine, the combination with a revolving hook, of an open-top thread receptacle within the hook-way having a front wall adapted to swing from an outer open position to an inner operative position, a stationary thread controller for guiding the loop inwardly above the open top of the receptacle, and a guide on the receptacle for guiding the loop after it leaves said stationary thread controller. 8. In a revolving hook sewing machine, the combination with a revolving hook having a race-way, of a thread receptacle, and a support for the thread receptacle mounted on said race-way and carrying a thread-guiding surface standing out from the support and extending continuously from the side the hook approaches the needle-way to and beyond said needle-way, for preventing the loop from being caught by the hook. 9. In a revolving hook sewing machine, the combination with a revolving hook and a thread holder positioned within the hook-way, of a continuous thread-guiding surface within the circumference of the hook-way and spaced horizontally from the vertical plane thereof, said surface extending from a point in proximity to the loop cast-off, upwardly and then toward and past the needle-way. 10. In a revolving hook sewing machine, the combination with a revolving hook having a race-way, of a thread holder, a support for the thread holder mounted on said race-way, a stationary thread controller for drawing the end portion of the loop inwardly above the thread holder at the front of the support, and another stationary thread controller having a guide surface above and forwardly of that on the first controller and extending across and to both sides of the needle-way. 11. In a revolving hook sewing machine, the combination with a revolving hook, a thread holder within the hook-way, having an upstanding thread-guiding surface forwardly of said hook-way, a stationary thread-controlling surface forwardly of said hook-way, and a second thread-controlling surface positioned intermediate and inwardly from said surface on the thread holder and said stationary surface whereby to draw the loop inwardly while it is guided on said surface on said thread holder and said first mentioned stationary thread-controlling surface. 12. In a revolving hook sewing machine, the combination with a revolving hook hav-

130

ing a race-way, a thread holder, and a support for the thread holder comprising a substantially annular part mounted on the race-way and having at its upper end a forwardly turned portion provided with fingers extending oppositely from said forwardly turned portion and shaped to provide thread-guiding surfaces.

13. In a revolving hook sewing machine, 10 a revolving hook body having a race-way in which is mounted a thread-guiding means, said body having a peripheral cutaway, and a hook point, the shank of which is detachably secured in said cutaway at one 15 side of said race-way, the hook point extending beyond and to the opposite side of the race-way.

14. In a revolving hook sewing machine, 20 a revolving hook body having a race-way in which is mounted a thread-guiding means, said body having a peripheral cutaway, a hook point, the shank of which is detachably secured in said cutaway at one side of said race-way, the hook point extending beyond and to the opposite side of the race-way, and a retaining ring detachably connected to the face of the revolving hook body and forming one side of the race-way and extending over and covering a portion of the 30 shank of the detachable hook.

15. In a sewing machine, the combination 35 with a revolving hook structure, of a thread holder, and a support for the thread holder associated with the revolving hook

structure and having a thread guiding surface disposed at the high portion of the hook point travel and extending continuously from front to rear of the needle-way beyond the same at the open side of the hook structure. 40

16. In a sewing machine, a revolving hook body having a raceway, a thread holder, a support for the thread holder mounted on the raceway and having a central aperture through which the thread holder extends, 45 said support having arms extending upwardly from the front and back of the needleway and joined together above the thread carrier and carrying means for holding the thread carrier support against rotation.

17. In a sewing machine, a revolving hook body having a raceway, a thread holder support mounted on said raceway, a thread receptacle pivotally mounted on said support 55 and having an open thread receiving top whereby the receptacle may be swung outwardly and inwardly from a thread-receiving position to an operative thread-holding position, and outstanding arms on said support extending from points adjacent to the front and back ends of said receptacle, upwardly and joined together above the receptacle and carrying an upstanding part 60 adapted for holding the support against 65 rotation.

ALBERT D. SMITH.
